UNITED STATES PATENT OFFICE.

CHARLES T. RICHMOND, OF CLEVELAND, OHIO, ASSIGNOR TO THE NATIONAL CARBON COMPANY, OF SAME PLACE.

DESIGN FOR A JAR.

SPECIFICATION forming part of Design No. 29,534, dated October 25, 1898.

Application filed August 18, 1898. Serial No. 688,935. Term of patent 7 years.

To all whom it may concern:

Be it known that I, CHARLES T. RICHMOND, a citizen of the United States, residing at Cleveland, in the county of Cuyahoga and State of Ohio, have invented and produced a new and original Design for Jars, of which the following is a specification, reference being had to the accompanying drawings, forming a part thereof.

The figures in the drawings are perspective views of my new design.

Figure 1 shows the jar standing on its bottom. Fig. 2 shows the jar in the same position, with a portion of it near the bottom broken away to show the interior; and Fig. 3 shows the jar bottom side up.

As shown in the drawings, the leading or material features of my design consist of the four substantially equal vertical sides $A' A^2$ $A^3 A^4$, each of which lies in a plane at sub-

stantially right angles to the adjacent sides, of the bottom A , uniting said four sides at substantially right angles thereto, and of the internal vertical partitions $B B'$, lying at right angles to each other and to the sides to 25 which they are united, thereby subdividing the jar into four substantially equal compartments.

Having described my invention, what I claim as new, and desire to secure by Letters 30 Patent, is—

The design for a jar, as herein shown and described.

In testimony whereof I hereunto affix my signature in the presence of two witnesses. 35

CHARLES T. RICHMOND.

Witnesses:

PHILIP E. KNOWLTON,
E. L. THURSTON.
